(57) CLAIM

The ornamental design for a wax heater, as shown and described.

DESCRIPTION

FIG. 1 is an upper left perspective view of a first embodiment of a wax heater, showing my new design.

FIG. 2 is a bottom right perspective view thereof.

FIG. 3 is a front view thereof.

FIG. 4 is a rear side view thereof.

FIG. 5 is a left side view thereof.

FIG. 6 is a right side view thereof.

FIG. 7 is a top view thereof.

FIG. 8 is a bottom view thereof.

FIG. 9 is an upper left perspective view of a second embodiment of a wax heater; and,

FIG. 10 is a rear view thereof.

In the drawings, the broken lines illustrate portions of the article forming no part of the claimed design.
